HORACE EVERETT, Pat'd FEB 8 1870
DESIGN FOR A METAL CAN.

WITNESSES { Mr. A. Sted.
Dr. B. Harding.

Horace Everett
by his Attr.
Howard and Son.

United States Patent Office.

HORACE EVERETT, OF PHILADELPHIA, PENNSYLVANIA.

Design No. 3,839, dated February 8, 1870.

DESIGN FOR METAL CANS.

The Schedule referred to in these Letters Patent and making part of the same.

I, HORACE EVERETT, of Philadelphia, county of Philadelphia, State of Pennsylvania, have invented a Design for a Metal Can, of which the following is a specification.

The figure in the accompanying drawing represents a perspective view of a can made according to my design.

The body of the can is of the form of a frustum of a cone; in other words, it has tapering sides, and decreases slightly in diameter toward the top. The can has also extending around it a rib or ribs, *a*, of the character clearly represented in the drawing.

I do not claim broadly a cylindrical, ribbed, or beaded can; but

I claim the design for a metal can, as described, and as represented in and by the accompanying drawing.

In testimony whereof, I have signed my name to this specification in the presence of two subscribing witnesses.

HORACE EVERETT.

Witnesses:

JOHN WHITE,
HARRY SMITH.
